CLAIM

The ornamental design for a reversible scroll directory, as shown and described.

DESCRIPTION

FIG. 1 is a top, right front perspective view of a reversible scroll directory showing my new design with the cover member in an open position;

FIG. 2 is a top plan view;

FIG. 3 is a rear elevational view;

FIG. 4 is a bottom plan view;

FIG. 5 is a front elevational view; and,

FIG. 6 is a right end and elevational view, the left end being a mirror image thereof.

FIGS. 2 through 6 have been drawn to a reduced scale with respect to FIG. 1. The hand and writing instrument depicted by means of broken lines in FIG. 1 are for illustrative purposes only and form no part of the claimed design.
